UNITED STATES PATENT OFFICE

2,587,486

CERVICAL SPECULUM

Jerome Kogan, Stamford, N. Y.

Application July 13, 1950, Serial No. 173,615

2 Claims. (Cl. 128—17)

1

The present invention concerns a cervical speculum, an instrument used by doctors to view the interior of the cervical canal. No instrument satisfactory for this purpose now exists.

The principal disadvantages of instruments used for this purpose are that the parts of the instrument which engage the cervix in order to dilate it for inspection defeat their purpose to a large degree by covering the tissue desired to be visualized; in addition the body of the instrument is in the line of sight between the cervix and the physician's eye, and the formation of the human body prevents any considerable manipulation of the instrument to overcome this.

An object of the present invention is the provision of a speculum in which the part which engages the cervix is of wire or similar construction so that it may enter and dilate the cervix without blocking the physician's view thereof.

Another object is that the body of the instrument shall be offset from the physician's line of sight to the cervix.

Other objects will appear as the description proceeds.

In accomplishing the above objects a speculum is provided having a scissors like body comprising handle portions pivoted together, finger rings, blade portions extending from the handle portions on the other side of the pivot, arm portions extending laterally from the blade portions, and elongated loop portions extending first toward each other from the arm portions and finally in a direction away from the pivot, the terminal portions being substantially parallel when the speculum is in closed position.

In operation, the terminal portions of the loops are inserted in the mouth of the cervical canal and the cervix gently dilated by moving the handles of the instrument. A good view of the tissue is possible because of the wire or similar construction of the loop, and because the handles and blades are offset from the loops.

Other objects of this invention will in part be obvious and in part hereinafter be pointed out. The invention accordingly consists in the features of construction, combinations of elements and arrangements of parts which will be exemplified in the constructions hereinafter described. In the accompanying drawing, in which is shown one of the various possible illustrative embodiments of this invention:

Figure 1 is a plan view of the speculum.

Figure 2 is a section on the line 2—2 of Figure 1.

2

Figure 3 is a side elevation looking in the direction of arrow 3 of Figure 1.

Referring now in detail to the drawings, the improved cervical speculum 10 comprises the handles 11 with finger rings 12, handles 11 being joined by the pivot 13 and each handle being integral with a blade portion 14. The medium line between the blades 14 is inclined approximately thirty degrees from the prolongation of the median line between the handles 11.

The arms 15 extend laterally from the blades 14 and substantially parallel to the axis of pivot 13.

The elongated loops 16 have inner portions 17 extending inwardly toward each other and terminal portions 18 extending away from pivot 13. Inner portions 17 comprise the legs 19, 20 extending substantially parallel one to the other and integral with their respective terminal portions.

20 The speculum is preferably made of corrosion resistant material such as stainless steel, and the loops 16 may be integral therewith or may be of stainless steel wire or the like firmly connected thereto.

25 In operation, the loops 16 are engaged in the os externum, the terminal portions 18 entering the canal and portions 17 acting as shoulders to limit the inward advancement. The mouth and canal can then be gently dilated to permit convenient inspection of the tissue, the wire construction of the loops permitting a good view of the tissue. The body of the instrument, comprising the handles 11 and blades 14 is offset from the physician's line of sight.

30 It will thus be seen that there is provided a device in which the several objects of this invention are achieved, and which is well adapted to meet the conditions of practical use. As various possible embodiments might be made of the above invention, and as various changes might be made in the embodiments above set forth, it is to be understood that all matter herein set forth or shown in the accompanying drawing is to be interpreted as illustrative and not in a limiting sense.

45 What is claimed is:

1. A cervical speculum comprising the combination with a pair of handles, a pivot connecting said handles and a blade portion connected to each of said handles and extending therefrom on the opposite side of said pivot, of arm portions extending from said blade portions substantially parallel to the axis of said pivot, an elongated loop portion connected to one of said 50 arm portions, said loop portion comprising an

inner portion extending substantially perpendicularly from said arm portion toward said other arm portion, said loop portion further comprising a terminal portion extending substantially perpendicularly from said inner portion and away from said pivot, and means mounted on said other arm portion and cooperating with said loop portion for engaging and distending the mouth of the cervix.

2. In a cervical speculum according to claim 1, 10 said cooperating means being a loop substantially identical to said first mentioned loop.

JEROME KOGAN.
